 tion of Delaware

Application August 1, 1942, Serial No. 453,264

5 Claims. (Cl. 129—28)

This invention relates to followers for vertical files and particularly files of the character used for housing correspondence and similar indexed records.

The invention provides a follower construction that is longitudinally adjustable in a drawer or the like, is constructed to occupy only a minimum of the filing space in said drawer, is mounted for swinging movement between forward and rearward tilted positions so correspondence or similar files supported thereby may be opened at the top to provide access to the filed matter, and provides a construction wherein a suitable latching means is normally operative to retain the follower against longitudinal adjustment in the drawer but is readily operable manually for releasing the latch means in order that the follower may be readily adjusted longitudinally in the drawer or other container in which it is mounted.

The invention comprehends the provision of a tilting follower construction for vertical correspondence and like files having a supporting member slidably mounted for longitudinal movement between the front and rear portions of the file carrying a tilting follower plate and having a latching means for normally retaining the supporting member in adjusted position against longitudinal movement, wherein the latching means is readily operable into released position regardless of the tilted position of the follower plate on the supporting member.

The invention further comprehends the provision of a follower construction wherein the entire construction is made of a relatively small number of parts constructed and assembled in a compact efficiently operating manner so that only a minimum of the filing space in the file container is occupied by the follower and yet the latching means is easily and readily operable in any tilting position of the follower plate relative to the supporting member so that the latching means can be operated to released position for convenient and ready adjustment of the follower longitudinally of the file container.

The invention further provides a follower construction that is readily assembled and cheap to construct although efficient in operation.

In the drawings:

Fig. 1 is a rear elevation showing the follower in vertical position in a file drawer with the drawer and channel member shown in cross section.

Fig. 2 is an enlarged vertical cross section taken on line 2—2 of Fig. 1 with the forward

and rearward tilted positions of the follower plate indicated by dot and dash lines.

Fig. 3 is a horizontal cross section taken substantially along line 3—3 of Fig. 2 with portions of the channel member broken away and shown in section for convenience in illustration.

Fig. 4 shows the supporting member and latch means carried thereby in perspective and in disassembled relation.

10 A file drawer or other suitable container for correspondence or similar files is indicated at 1. It will be understood that the term drawer will be used to indicate any type of holder or container that may be useful with the follower construction herein disclosed. Drawer 1 has a bottom wall 2 and upstanding side walls 3 arranged in spaced parallel relation at the opposite sides of bottom 2. The central portion of bottom wall 2 is formed with an offset portion 4 for receiving channel member 5 formed to provide guideways along opposite sides thereof. The upper flanges of channel member 5 terminate in substantially the same plane as the upper face of the bottom wall 2 in the manner shown in Fig. 1. This channel member is formed with two rows of openings 6 extending longitudinally thereof and spaced inwardly a slight distance from the guide portions at opposite sides of the channel member. Perforations 6 form a keeper means or portions on the channel with which latch members cooperate as hereinafter described.

35 A follower carriage or supporting member 7 is substantially U-shape in form, has a transverse bar or section 8 and a pair of leg portions forming spaced parallel guide members 9 extending from opposite ends of transverse bar 8. Guide members 9 are provided with bearing projections 10 at the front and rear ends on the upper and lower edges thereof for slidable contact with the upper and lower portions in the guideways of channel member 5. Laterally extending ribs 11 at the front and rear ends of each guide member 9 extend outwardly at each side of supporting member 7 and engage in the guideways of channel member 5 in slid- 40 able relation for controlling sidewise movement. These guide members with the projections 10 and 11 slidably support supporting member or follower carriage 7 for longitudinal sliding move- 45 ment in channel member 5 in a free and easy manner at the same time retaining the supporting member against tilting and sidewise movement in the channel member. The upper edge of transverse bar 8 of supporting member 7 is

provided with an extension forming a hinge knuckle 12.

A follower plate 13 is formed of sheet metal or other suitable material. Follower plate 13 is formed along the bottom edge to provide a tubular portion 14 at opposite sides of a central cutout section indicated at 15 so arranged that cutout section 15 will receive hinge knuckle 12 in order that the passage in the hinge knuckle will be in axial alignment with the bore of tubular portion 14. A hinge pin 16 is inserted in tubular portion 14 and through hinge knuckle 12 for hingedly connecting follower plate 13 to supporting member or follower carriage 7 in the manner illustrated in Figs. 1 and 2.

The upper central portion of follower plate 13 is provided with a curved flange 17 adapted to form a convenient grip for manually engaging the follower to operate it between its forward and rearward inclined positions in a drawer. The central portion of curved flange 17 is formed with an aperture 18 through which extends the upper end of operating bar or member 19 having a laterally extending handle portion 20 formed on the free end above follower plate 13.

Operating bar 19 extends between the bottom and top edges on the rear face of plate 13 and is guided at the lower end by stud 21 extending through slot 22 formed in bar 19. Stud 21 is suitably secured to follower plate 13. The lower end of operating bar 19 is formed with an offset portion 23 in spaced parallel relation to the rear of follower plate 13. The lower end of offset portion 23 is notched as indicated at 24 to provide a pair of inclined operating edges 25.

A pair of latch levers 26 are pivotally mounted in end to end relation intermediate their ends on a pair of spaced studs 27 carried by transverse bar 8 of supporting member 7. The adjacent ends of latch levers 26 are formed to provide operating fingers 28. These fingers are formed by laterally extending flange portions on the adjacent ends of levers 26 arranged to lie in the path of movement of the inclined edges 25 of operating member 19. The outer free ends of latch levers 26 are formed with lateral flange extensions 30 having the lower end portions thereof formed to provide projections to engage in perforations 6 in channel member 5.

A spring member 31 is formed with a pair of coiled portions spaced apart a distance equal to the distance between the axes of studs 27 so that the studs may pass through the coil portions of spring 31. The studs support the spring so the resiliently actuated end portions 32 can be extended outwardly into engagement with the outer free ends of latch levers 26 in notches 33 formed in the upper edges of the laterally extending flange portions 30 thereof. Spring 31 is normally operative through end portions 32 to move latch levers 26 in a direction so that the projections on the lower ends of flanges 30 will normally engage in keeper openings 6. This moves the inner ends of latch levers 26 upwardly, fingers 28 moving upwardly under the normal action of the spring to be in position to engage the inclined edges 25 of operating bar 19. The pivotal movement of latches 26 about studs 27 under the operation of spring 31 is limited by the engagement of the inner upper edges of latches 26 with stop projections 34 formed on transverse bar 8 as clearly shown in Fig. 4.

In view of latch members 26 being normally operated into latching position by spring 31 with 75

the inner ends retained in engagement with the ends of stops 34, it is not necessary to provide any means for operating bar 19 since fingers 28 will support bar 19 in all positions of follower plate 13 in a position ready for manual operation. This operation is obtained by constructing spring 31 to have the desired strength for securing the operation of both latches 26 and operating bar 19. By manually depressing operating bar 19 by engaging finger piece 20 and pushing down thereon, movement of bar 19 downwardly relative to follower plate 13 will cause offset part 23 to have the inclined edges 25 thereof move finger extensions 28 downwardly for rocking latch levers 26 about their pivots against the tension of spring 31 so that the projections on flanges 30 will be disengaged from the securing means or perforations 6. Upon release of downward pressure on bar 19, spring 31 will return the bar to the upward limit of movement relative to follower plate 13 while latches 26 will be returned to the position where the inner ends engage stops 34. Whenever bar 19 is pushed downwardly to disengage the flanges 30 of latches 26 from apertures 6, follower plate 13 with its supporting member or carriage 7 may be longitudinally adjusted by sliding carriage 7 longitudinally in channel member 5 to the desired position. When this position is reached, release of manual operation to hold bar 19 in the downwardly depressed position will provide for the upward sliding movement of bar 19 to the position shown in Figs. 1 and 2, for example, where latch members 26 will return to the operative position for latching the follower structure in an adjusted position.

The upper corners of follower plate 13 at the sides of the drawer are cut off in angular relation and at a distance above the upper edges of the sides of the drawer, the upper side portions of follower plate 13 carry rollers 35 extending laterally outward from the side edges of carrier plate 13 over the side walls 3 of the drawer. These rollers 35 are arranged so they will extend in spaced relation above the upper edges of the side walls of the drawer when the follower plate is in the vertical position as shown in Figs. 1 and 2. When the follower plate is moved into a forwardly or rearwardly tilted position, rollers 35 will engage with the upper edges of the side walls 3 of the drawer and limit the tilting movement of follower plate 13. Tilting movement of the follower plate is limited by rollers 35. The follower plate is usually supported in one of the two positions as shown by dot and dash lines in Fig. 2 of the drawings. Only a portion of the follower plate is indicated in dot and dash lines at the left-hand side of Fig. 2.

Lateral flanges 30 are provided with an inclined bottom edge portion 36 arranged so that the inclined edge operates to cam the projections on latches 26 out of perforations 6 so that the follower construction can be moved forwardly in a drawer or tray without operating bar 19 to release latch members 26. This will provide for convenient movement of the follower construction up against the rear portion of a group of papers in the drawer for positioning the follower to properly support the file papers in the drawer. Rearward movement of the follower will be prevented by latch members 26 having the projections on the lower ends of flanges 30 dropping into respective openings 6 in a manner as clearly illustrated in Fig. 2.

When the follower is in latched position it will be understood that follower plate 13 may be moved on the hinge connection with supporting member 7 either forwardly or rearwardly to the inclined positions indicated by the dot and dash lines in Fig. 2. Follower plate 13 will normally be supported in one of these inclined positions so that files in the drawer can be opened by letting the portion to the rear of the point desired incline or lean rearwardly on follower plate 13 while the remaining files will lean forwardly against the front of the drawer opening up a space at the upper ends of the files so a file operator can have convenient access to the correspondence at the point of opening in the file.

The follower construction can be moved rearwardly in a most convenient manner by depressing bar 19 through manual engagement with handle extension 20, regardless of the tilted position in which the follower plate 13 may be at the time it is desired to operate latch members 26. The latch members will be moved into inoperative position by the operation of operating bar 19 so the follower may be moved rearwardly in the drawer for adjustment at any time with follower plate 13 positioned in any of the various angles that it occupies between the forward and rearward tilting positions indicated when rollers 35 will engage the upper edges of the sides 3 of the drawer.

The structure of follower carriage or supporting member 7 is such that it will have free sliding movement in channel member 5 and be retained against rocking movement in the channel member in such a way that it will have free sliding operation between the front and rear ends of the drawer in the channel member without sticking or catching. The latches are of simple construction, cheap to manufacture and readily assembled in operative position for maintaining the follower normally in adjusted position. Yet, the latches are readily operable so that the follower may be easily adjusted in the drawer while follower plate 13 may be in any of its tilted positions.

The follower construction uses only a single thickness of sheet metal in forming plate 13 while bar 19 is a thin sheet metal strip, this construction providing for the use of only a minimum amount of file space in the drawer, considerably less than many other known types of follower constructions that take up a greater space longitudinally of the drawer. The construction of supporting member 7 is such that it lies substantially wholly within channel 5 without having wide projecting parts extending above the bottom of the file drawer, so as to cooperate with the follower plate in using only a minimum amount of filing space within the drawer.

The supporting member is provided with an aperture 40 in the cross bar 8 to receive the conventional drawer rod. The U-shape of the supporting member receives the tabs on guide cards between guide members 9 and facilitates its mounting and free operation in the channel member.

The invention claimed is:

1. In a followed construction for drawers and the like wherein the drawer has a bottom wall and side walls extending upwardly therefrom in spaced parallel relation, and a channel member extends longitudinally on the bottom wall, the combination of a supporting member slidably

longitudinally in said channel member, a follower plate hingedly mounted on said supporting member for swinging movement thereon between forwardly and rearwardly tilted positions, means for limiting the tilting movement of said follower plate, latch means on the supporting member normally operative to engage said channel member and retain said supporting member against longitudinal movement therein, and an operating member movably mounted on said follower plate manually operable in all positions of said plate for engaging and moving said latch means into inoperative position whereby said follower plate and supporting member may be longitudinally adjusted in said channel member.

2. In a follower construction for drawers and the like wherein the drawer has a bottom wall and side walls extending upwardly therefrom in spaced parallel relation, and a channel member extends longitudinally on the bottom wall, the combination of a supporting member slidably longitudinally in said channel member, a follower plate hingedly mounted on said supporting member for swinging movement thereon between forwardly and rearwardly tilted positions, means for limiting the tilting movement of said follower plate, a pair of levers pivotally mounted on said supporting member and having one end of each lever formed to engage keeper portions formed in said channel member for retaining said supporting member against longitudinal movement in said channel member, resilient means carried by said supporting member for normally moving said levers into latching position, and an operating bar slidably mounted on said follower plate with one end extending above the upper edge of said follower plate for manual engagement to slidably move said bar on said follower plate, said operating bar having the lower end formed to engage both of said levers in any position of said follower plate on said supporting member between said forwardly and rearwardly tilted positions whereby manual operation of said operating bar will move said latching levers into inoperative position for adjustment of said follower plate and supporting member longitudinally in said channel member.

3. In a follower construction for drawers and the like wherein the drawer has a bottom wall and side walls extending upwardly therefrom in spaced parallel relation, and a channel member extends longitudinally on the bottom wall, the combination of a U-shaped supporting member having a cross member extending transversely between the sides of said channel member and leg portions extending from opposite ends of said cross member slidably guided in said channel member along guideways on opposite sides thereof for retaining said supporting member in said channel for longitudinal sliding movement, a follower plate hingedly connected at the lower edge to said cross member for swinging movement on said supporting member between forwardly and rearwardly inclined positions, a pair of latch levers pivotally mounted on said cross member in spaced end to end relation, said latch levers having the outer ends thereof formed for engagement with complementary parts of said channel member for latching said supporting member to said channel member against longitudinal movement, means normally retaining said latch levers in latching position, and manually operable means on said follower plate having portions for engaging the adjacent ends of said latch levers in all positions of said

follower plate between said forwardly and rearwardly tilted positions for manually moving said latch levers into released position to provide for longitudinal adjustment of said follower plate and supporting member relative to said channel member.

4. In a follower construction for drawers and the like wherein the drawer has a bottom wall and side walls extending upwardly therefrom in spaced parallel relation, and a channel member extends longitudinally on the bottom wall, the combination of a U-shaped supporting member having a cross member extending transversely between the sides of said channel member and leg portions extending from opposite ends of said cross member slidably guided in said channel member along opposite sides thereof for retaining said supporting member in said channel member for longitudinal sliding movement, a follower plate hingedly connected at the lower edge to the cross member for swinging movement on said supporting member between forwardly and rearwardly inclined positions, a pair of latch levers pivotally mounted on said cross member in spaced end to end relation, said latch levers having the outer ends thereof formed for engagement with complementary parts of said channel member for latching said supporting member to said channel member against longitudinal movement, means normally retaining said latch levers in latching position, and an operating bar slidably mounted on said follower plate in upright position having the upper end extending above the upper free edge of said follower plate for manual engagement in the operation of said bar and the lower end being formed with a pair of spaced parts for engaging the adjacent ends of said latch levers and operable in manual operation of said operating bar to engage and move said latch

levers into released position whereby said follower plate and supporting member may be longitudinally adjusted in said channel member.

5. A tilting follower for drawers and the like, comprising a channel member having guide portions along opposite sides thereof and keeper means adjacent said guide portions extending longitudinally throughout the length thereof, a supporting member having guide members slideable in the guideways of said channel member for slidably mounting said supporting member for longitudinal movement in said channel member, said supporting member having a transverse supporting section extending between said guide members, a follower plate having the lower edge provided with a hinge connection to said transverse section of said supporting member for mounting said follower plate on said supporting member for swinging movement between forward and rearward tilted positions, a pair of latch members mounted in end to end relation on said transverse section for pivotal movement relative thereto, said latch members having latch portions for engagement with the keeper means in said channel, resilient means for normally moving said latch members into engagement with said keeper means for retaining said supporting member against longitudinal movement on said channel member, and an operating bar slidably mounted on said follower plate and formed at the lower end with a pair of oppositely inclined portions for engaging the free ends of said latch members and at the opposite end with a finger piece for manual operation to slidably move said operating bar to operate said latch members into released position to provide for longitudinal adjustment of said follower plate and supporting member in said channel member.
